UNITED STATES PATENT OFFICE.

EMMA ALMA SMITH, OF STANDISH, MICHIGAN.

OIL-BURNING STOVE.

1,310,254.

Specification of Letters Patent. Patented July 15, 1919.

Application filed November 10, 1917. Serial No. 201,316.

To all whom it may concern:

Be it known that I, EMMA ALMA SMITH, a citizen of the United States, residing at Standish, in the county of Arenac and State 5 of Michigan, have invented new and useful Improvements in Oil-Burning Stoves, of which the following is a specification.

This invention relates to improvements in oil burning stoves, and resides in the construction, combination and arrangement of parts set forth in the following specification and falling within the scope of the appended 10 claim.

In the drawing:

15 Figure 1 is a perspective view of an oil burning stove constructed in accordance with the present invention, and

Fig. 2 is a top plan view, parts being broken away and parts being shown in section.

20 Fig. 3 is a vertical longitudinal sectional view through one of the burners.

While in the accompanying drawing I have illustrated my improved stove as provided with six burners, three to the front of the stove and three to the rear thereof, it is to be understood that any number of burners may be employed. The burners are indicated by the characters 2, and are of the 25 usual construction employed. The usual means 7 are employed for regulating the wicks in the burners.

The oil tank is preferably located at one 30 side of the stove and is indicated by the numeral 9. Connected to this tank are two oil conveying pipes 10 and 11 respectively, the pipe 10 leading to the rear series of burners, the pipe 11 being disposed in a line with the outer series of burners, and the numerals 12 designate the branch pipes connected 35 with the said pipes 10 and 11 for conveying the oil directly to the wicks in the burners. Each of the branch pipes is provided with a valve 13, the same being preferably provided 40 with an extending stem to which is connected an angular arm 14, and to the said angular arm is secured one end of a rod 15, the opposite end of each of said rods being provided with a headed knob 16. It will be 45 noted that the heads of the rods 15 are arranged beyond the outer side of the stove.

By this arrangement the oil control of the several burners may be regulated in a convenient manner and without danger of actuating other than the desired valve for a 55 particular burner. The wick control rods 7 are disposed outward of the headed ends of the rods 16 as clearly illustrated in Fig. 2 of the drawings and being arranged in pairs, one above the other for the respective 60 front and rear burners the wicks of the said burners may be accurately adjusted in a manner convenient to the user of the stove.

The construction is extremely simple, and as any or all of the valves may be readily 65 regulated from the front of the stove the wicks in any desired number of burners may be readily ignited or extinguished. The regulating means for the wicks, it will be noted, is arranged at the front of the stove, 70 but at a suitable distance away from the knobs 16 for the valve operating rods 15, so that the wicks may be readily regulated to produce the desired flame.

From the above description, taken in connection with the accompanying drawing, the simplicity of the device, as well as the advantages thereof will, it is thought, be perfectly apparent to those skilled in the art to which such invention appertains without 75 further detailed description.

Having thus described the invention, what I claim is:

An oil burning stove including a plurality of burners arranged in series, a fuel 85 tank, supply pipes leading therefrom to the front and rear series of burners, a valve for the oil inlet for each of the burners, the stem of each of the valves having an angle arm thereon, a rod connected with each of said 90 arms and extending through and beyond the outer face of the stove and the ends of the said rods being headed, wick controlling means for each of the burners including rods extending through the outer face of the stove 95 and having their ends headed, and the heads of the last mentioned rods being disposed in parallelism and away from the heads of the fuel controlling rods.

In testimony whereof I affix my signature. 100

EMMA ALMA SMITH.
